UNITED STATES PATENT OFFICE.

DELIA G. FULCERI, OF NORTH WEYMOUTH, MASSACHUSETTS.

HAT-FASTENER.

1,222,281.

Specification of Letters Patent. Patented Apr. 10, 1917.

Application filed June 30, 1916. Serial No. 106,930.

To all whom it may concern:

Be it known that I, DELIA GIOVANNA FULCERI, a subject of the King of Italy, residing at North Weymouth, in the county of Norfolk, in the State of Massachusetts, have invented a certain new and useful Improvement in Hat-Fasteners, of which the following is a specification, reference being had to the accompanying drawings.

10 This invention relates to that class of hat fasteners which comprise, essentially, a comb that is slidably mounted in a guide-plate secured fixedly to the under side of the hat brim and my present object is to improve 15 such fasteners by providing simple and inexpensive means for retaining the comb in its operative position and also for protecting the points of the comb teeth when the comb is in its inoperative position, that is to say, 20 when the comb is withdrawn from the hair.

Incidentally, I have also secured the guide-plate to the hat in such manner that the said plate may be adjusted as to its 25 position relative to the hat crown, and so that the comb may be caused to enter the hair at any desired angle or inclination.

In order to explain my invention clearly I have provided the annexed drawing in 30 which Figure 1 is a central, vertical, sectional view of a hat showing two of my improved fasteners mounted on the said hat in opposition to each other; one of said fasteners being shown as if it were pushed forward into engagement with the hair of the wearer 35 of the hat, while the other fastener shows the comb withdrawn from the hair.

Fig. 2 is a perspective view of the complete fastener, with the comb in its operative position and secured to the guide-plate and 40 Fig. 3 is a similar view showing the comb withdrawn and the ends of the teeth concealed within the guide-plate.

Referring to these drawings the letter *a* indicates a hat. The letter *b* denotes my 45 guide-plate the same being formed, as here shown, with offset end portions which terminate in feet *b'* which are perforated so that the said feet may be stitched to the hat, or to the hat lining, at the point where the 50 crown and brim of the hat meet, and so that a flexible connection is made as will be seen by reference to Fig. 1 of the drawings, thus rendering it possible and convenient to enter the comb in the hair at that desired angle.

55 The comb is denoted as a whole by the reference letter *c* and it comprises a back

plate *c'* and a plurality of teeth, the said comb being adapted to slide in the guide-plate *b* a limited distance, the limit of movement in one direction being governed by 60 pins *d*, in the guide plate, which enter slots *c²* in the comb and in the other direction by a headed stud *e*, in the back-plate *c'*, which stud is adapted to enter a slot *b²* in the guide-plate; the entrance to slot *b²* being 65 of such restricted width that the stud *e* may be forced therethrough and the comb is thus prevented from accidental separation from the guide-plate when the fastener is in use.

The comb may, however, be withdrawn 70 from the guide-plate by grasping the head of the stud *e* and forcibly removing the said stud from the slot *b²*.

It should be noted that, when the comb is thus withdrawn to its greatest extent, the 75 points of the comb teeth pass under the plate *b* and are thus completely withdrawn from the hair, and kept from engagement with the hair while the hat is being removed from or placed upon, the head. This 80 is an important construction when viewed in comparison with other combs of this general type in which the teeth of such combs project beyond their supporting plate and are invariably being caught by the hair 85 when the hat is being removed, to the great annoyance of the wearer, as well as the disarrangement of her hair.

When it is desired to wear a hat having 90 fasteners of my described type, the comb is first drawn outward, as seen in Fig. 3; the hat is then placed upon the head and the comb is forced upward under plate *b*, and into the hair, until the stud *e* has been forced into the slot *b²*. 95

When it is desired to remove the hat it is only necessary to grasp the knob of stud *e* with a thumb and finger and release the stud from the slot, when the comb may be completely withdrawn from the hair and the 100 hat can be removed from the head.

The flexible connection between the guide plate *b* and the hat renders it possible, as I have already stated, to vary the angle or inclination of the comb with respect to the 105 head of the wearer of the hat and this is particularly desirable because of the facts that some hats are worn high upon the head while others are worn low-down, and I may add that the different modes of dressing the 110 hair also make it desirable, in fact necessary, that the comb shall be inserted in the

hair at relatively different angles or inclinations.

Having thus described my invention I claim as new and wish to secure by Letters Patent:—

A hat fastener comprising an elongated guide member offset at its ends to provide feet and perforated whereby to be engaged flexibly with a hat, the one edge of said 10 guide member having a slot therein with a constricted opening forming substantially a latch, a comb operating through said guide member and having its end teeth slotted lon-

gitudinally and closed at both ends, pins mounted transversely in said guide member and entering said slotted teeth to limit the movement of said comb in one direction, the teeth of the comb in the latter position being entirely within said guide member and isolate from the hair and a stud 20 upstanding from the head of said comb and adapted to be engaged with the slotted latch in said guide member, to limit the movement of the comb in the opposite direction and retain the same in effective position.

DELIA G. FULCERI.
